Primary Examiner — Susan M Lee*Assistant Examiner* — Linda G. Brooks(74) *Attorney, Agent, or Firm* — Hedman & Costigan, P.C.; James V. Costigan(57) **CLAIM**

The ornamental design for a lighting apparatus, as shown and described.

DESCRIPTION

FIG. 1 is a rear perspective view of a lighting apparatus according to the present invention;

FIG. 2 is a front view of the lighting apparatus according to the present invention;

FIG. 3 is a back view of the lighting apparatus according to the present invention;

FIG. 4 is a left side view of the lighting apparatus according to the present invention;

FIG. 5 is a right side view of the lighting apparatus according to the present invention;

FIG. 6 is a top view of the lighting apparatus according to the present invention; and,

FIG. 7 is a bottom view of the lighting apparatus according to the present invention.

The broken lines which define the bounds of the claimed design form no part thereof.
